UNITED STATES PATENT OFFICE

HOWARD A. LAY, OF SHADYSIDE, OHIO

DESIGN FOR A PLATE OR SIMILAR ARTICLE

Application filed August 25, 1931. Serial No. 40,929. Term of patent 7 years.

To all whom it may concern:

Be it known that I, HOWARD A. LAY, a citizen of the United States of America, and resident of Shadyside, county of Belmont, and State of Ohio, have invented a new, original, and ornamental Design for a Plate or Similar Article, of which the following is a specification, reference being had to the accompanying drawing, in which the single figure is a top plan view of a plate or similar article showing my new design.

The design comprises a thrice symmetri-

ally repeated surface decoration applied to the article, of which somewhat more than one repeat is shown in full lines in the drawing, the two ellipses shown in broken lines indicating the positions of the repeats of the similarly shaped medallion-like figure shown in the full line representation of the design.

I claim:

The ornamental design for a plate or similar article, substantially as shown and described.

HOWARD A. LAY.
